UNITED STATES PATENT OFFICE

165,907

FOLDING CHAIR

Fred E. Chehak, Cedar Rapids, Iowa

Application July 9, 1951, Serial No. 15,799

Term of patent 14 years

(CL. D15—8)

To all whom it may concern:

Be it known that I, Fred E. Chehak, a citizen of the United States of America, residing at Cedar Rapids, county of Linn, and State of Iowa, have invented a new, original, and ornamental Design for a Folding Chair, of which the following is a specification, reference being had to the accompanying drawing, forming a part thereof, wherein:

I claim:

The ornamental design for a folding chair, as shown.

FRED E. CHEHAK.
